UNITED STATES PATENT OFFICE.

MARLETT DAWES BODDY, OF LONDON, ENGLAND.

MARINE LIFE-SAVING APPLIANCE.

Application filed June 26, 1923. Serial No. 647,871.

To all whom it may concern:

Be it known that I, MARLETT DAWES BODDY, a subject of the King of Great Britain, of 12 Dartmouth Place, Blackheath, 5 London, S. E. 10, England, have invented new and useful Improvements in Marine Life-Saving Appliances; and I do hereby declare the following to be a full, clear, and exact description of the same.

10 The present invention relates to marine life-saving appliances of any kind employing cork blocks to give the necessary buoyancy, and it has for its general object to provide an improved construction of such 15 which will be more comfortable and less dangerous to wear than such appliances generally are.

It has been found by experience that when a person jumps into the sea from a vessel 20 the shock of striking the water tends to displace any life-saving appliance worn by the person violently upwards and if the appliance contains cork blocks these are likely to cause damage to the wearer's head which 25 may result in producing insensibility or in some cases even in breaking the wearer's neck. Loss of consciousness causes the wearer's head to drop forwardly with the result that the balance of the wearer and 30 the life-saving appliance is destroyed so that the wearer's mouth may remain under water until he becomes drowned. Further in rough water the wearer's head is likely to become damaged by blows given thereto 35 by the cork blocks due to the buffeting of the waves.

More specifically the primary object of this invention is to obviate the above described disadvantages by providing an improved 40 construction of appliance in which a pad of soft material, such as kapok, or the equivalent thereof, is disposed between the cork blocks and the chin of the wearer, and forms a soft cushioning member adapted to 45 absorb shocks or blows from the cork blocks.

A further object is to enable the appliance to be used with safety by either children or adults, and a still further object is to so construct the appliance that it is reversible, 50 i. e. is perfectly safe whichever way it is put on by the wearer. Still another object is to provide a construction which will enable

the use of kapok, or the like, to be entirely dispensed with.

In constructing the improved appliance 55 in accordance with my invention the cork blocks of the appliance are cut away to form a recess beneath the chin of the wearer and some means of a soft nature are provided for preventing the chin of the wearer 60 from entering the recess. Such means may consist of kapok or like pads placed in the recess, or may consist of a band of canvas or other textile material stretched across the mouth of the recess.

65 Further features of the invention will appear from the following description of the accompanying drawings illustrating the same and from the claims more particularly defining the invention, which are appended 70 hereto and form part of this specification.

In the drawings:—

Figure 1 is a plan view of one construction of appliance laid out flat,

Figure 2 is a similar view of a second 75 construction of appliance,

Figure 3 is a perspective view of the second construction of appliance fastened as it would be upon a person's body, and

Figures 4, 5 and 6 are perspective plan 80 views of three other constructions of appliance when laid out flat.

In Figures 1, 4, 5 and 6 the invention is shown applied in three different manners to life-saving appliances of the "circular" 85 type, consisting of front and rear buoyant compartments connected by textile material 1 provided with a head opening 2 between the compartments, the whole being surrounded by a peripheral hem 3 of textile material containing draw strings 4 by which the side portions 5 of the hem may be contracted beneath the armpits of a wearer whose arms are passed through the arm holes 6.

95 In Figures 2 and 3 the invention is shown applied to life-saving appliances of the "reversible waistcoat" type which comprises a rear compartment connected at each end by portions of textile material each having an arm hole 7 therein to a front buoyant compartment, draw strings 4^a being provided for tightening up the appliance and securing it to the wearer in well known 100

manner. When in use, as shown in Figure 3, the two front buoyant compartments come together and are exactly equivalent in buoyancy and buoyant action to the rear compartment, so that the appliance may be put on back to front without affecting its action. Similarly the appliance is such that it may be put on either way up without affecting its action.

10 Referring to Figures 1 and 4 the front and back buoyant compartments consist of or contain cork blocks 8 arranged in pairs, and according to the invention the adjacent corners of each block nearest the head opening 2 are cut away. In Figure 1 the recesses so formed are filled with pads 9 stuffed with kapok or other buoyant material of a soft nature, these pads not only serving as a soft cushion for the wearer's chin but also preventing uprush of water through the space between the edges of the blocks into the wearer's mouth.

15 In Figures 2 and 3 recesses are formed centrally in the upper and lower edges of the cork blocks 10 of the back compartment, and the upper and lower meeting corners of the front compartments 11 are cut away, so that recesses are formed when the appliance is fastened with the edges of the front 20 compartments meeting. The recesses in the rear compartment are filled with kapok or like pads 12 and the corners of the front compartments are filled in with kapok or like pads 13, these being in size and shape 25 equal to half of the pads 12. Thus a soft cushion or rest for the chin is provided whichever way up or whichever way round the appliance is put on by the wearer.

30 In Figure 4 recesses are formed in the cork blocks similarly to Figure 1, but instead of filling them in with kapok pads, bands 14 of canvas, or other textile material are stretched across the mouths of the recesses, being secured, for example, by stitching 35 to the canvas or the like containing the cork blocks, so as to prevent the wearer's chin from entering the recesses and coming into contact with the cork blocks. It will be appreciated that as there is no cork immediately beneath the bands 14, no damage 40 is inflicted on the chin by upward movements of the appliance. If found necessary in order to keep the bands 14 sufficiently taut I may provide rigid stiffening members 45 50 55 15 of wood, or the like, across the cork blocks to prevent them from hinging in relation to each other.

60 In Figure 5 the construction is similar to that of Figure 4 except that single cork blocks are used for the back and front compartments respectively, thereby avoiding

any need for stiffening members, such as 15 of Figure 4.

In Figure 6 the textile covering 18 of two of the cork blocks 16 is shown partially turned back, and it will thus be apparent that the construction is similar to that shown in Figure 1, but the pair of cork blocks 16 have their inner edges cut off at an angle so as to leave a triangular space 70 between the blocks which is filled in by a triangular bag 17 of textile material stuffed with kapok, or the like, the base of the bag 17 being adjacent the neck opening of the appliance. The blocks 16 may be so cut 75 that the bag 17 extends only partly or wholly as shown from top to bottom of the blocks.

In the foregoing constructions in which kapok pads are used, the efficiency of the 80 appliance will be somewhat increased owing to the greater buoyancy of kapok than that of an equal volume of cork. It will be obvious that if desired only the front compartments may be recessed as hereinbefore described, in which case the appliance would not be completely reversible. Further the appliances shown in Figures 1, 4 and 5 may be recessed in the lower edges of their compartments in addition to the upper edges, if 90 desired.

What I claim is:—

1. A marine life-saving appliance of the kind set forth comprising in combination a buoyant compartment formed of solid cork, 95 a recess in the edge of said compartment which lies nearest the head of the wearer, and means of a soft nature associated with said recess for preventing the chin of the wearer from entering therein. 100

2. A marine life-saving appliance comprising front and back buoyant compartments made of cork blocks, a textile support for said compartments, a neck opening in said support between the front and back 105 compartments, arm holes in said support at the sides of said compartments, draw strings for contracting the periphery of said support, recesses in the cork blocks adjacent the neck opening, and a packing of kapok in 110 said recesses.

3. A marine life-saving appliance of the reversible type comprising back and front buoyant compartments of equal buoyancy, recesses in said compartments positioned to 115 come beneath the head of the wearer, and means of a soft nature associated with said compartments adapted to prevent the chin of the wearer from entering said recesses.

4. A marine life-saving appliance as set forth in claim 1, wherein the buoyant compartment is made up of two blocks of cork 120

disposed side by side and having their adjacent edges cut away to form a V-shaped recess between the blocks and a triangular bag filled with kapok is disposed in said recess.

5. In a marine life-saving appliance a rectangular cork block recessed centrally of one of its longest edges, and a pad of kapok

disposed in said recess to complete the rectangular shape of said block. 10

In testimony whereof I affix my signature in presence of two witnesses.

MARLETT DAWES BODDY.
